UNITED STATES PATENT OFFICE.

RAYMOND TYZACK, OF SHEFFIELD, ENGLAND.

DESIGN FOR A MASCOT FOR MOTOR ROAD VEHICLES.

Application filed February 16, 1922. Serial No. 747. Term of patent 3½ years.

To all whom it may concern:

Be it known that I, RAYMOND TYZACK, a subject of the King of Great Britain, residing at city of Sheffield, England, have invented a new, original and ornamental Design for a Mascot for Motor Road Vehicles of which the following is a specification, reference being had to the accompanying drawing forming part thereof.

The figure is a view of a mascot for motor road vehicles, showing my new design.

I claim the ornamental design for a mascot for motor road vehicles as shown.

RAYMOND TYZACK.
